EDMUND W. QUINCY AND WILLIAM FISHER, OF LACON, ILLINOIS.

Letters Patent No. 76,943, dated April 21, 1868.

IMPROVEMENT IN OPERATING FERRY-BOATS.

The Schedule referred to in these Letters Patent and making part of the same.

TO ALL WHOM IT MAY CONCERN:

Be it known that we, EDMUND W. QUINCY and WILLIAM FISHER, of Lacon, in the county of Marshall, and State of Illinois, have invented a new and useful Improvement in the Mode of Propelling Ferry-Boats; and we do hereby declare that the following is a full, clear, and exact description of the construction and operation of the same, reference being had to the annexed drawings, making a part of this specification, in which—

Figure 1 is a plan view of the drums, and

Figure 2 is a side elevation.

To enable others skilled in the arts to make and use our invention, we will proceed to describe its construction and operation.

This invention consists of an arrangement of drums on a ferry or canal-boat, and on the shores, at the ends of the route of such boat, and of a rope in connection with said drums, whereby the boat is propelled without the use of paddle-wheels, as will hereinafter more fully appear.

a a' a'' represent three wooden drums, placed in suitable supports, longitudinally of the vessel. The central drum, *a'*, is encircled with a wire rope, *b*, which passes from it in opposite directions, and each part running over one of the pulleys *a a''*, extends to the shore at each end of the route, and is there attached to a windlass, *d*. To the central drum, motion is communicated in either direction by means of steam or other agent. The rope *b* is thus wound up in one direction, and unwound in the other, and the boat propelled accordingly. The weight of the ropes between the drum *a'* and the windlasses *d*, insures a firm gripe of said chains upon said drum *a'*, and prevents any slipping. The continually-increasing distance behind the vessel, takes up the slack of the unwound rope. The function of the windlasses *d* is to make slack between them and the vessel whenever that is desired, in order to let other craft pass over the rope, and to take up the slack when such craft has passed. In order to this, the windlasses are provided with a sufficient number of extra coils of rope.

It will be perceived that the position of the drums on the vessel is in a diagonal line, and that the drums are provided with vertical flanges, *e*.

There is only one point where the parts of the rope *b* could possibly abrade each other, and that is at the upper part of the central drum, *a'*, where they pass each other. All possibility of such abrasion is removed by the flanges *e* of the end drums, which draw the parts of the rope away from the vertical plane which cuts longitudinally the centre drum.

The advantage of our arrangement is that it dispenses with the use of paddle-wheels, and thus not only economizes the power necessary to drive such wheels, but enables boats of light draught to be run in canals, and other shoal waters, where paddle-wheels are impracticable or injurious.

Having thus described our invention, what we claim as new, and desire to secure by Letters Patent, is—

A ferry or other boat, provided with flanged drums *a a' a''*, arranged with reference to the prevention of the abrasion of the parts of the draught-rope upon each other, in the manner described.

E. W. QUINCY,
WM. FISHER.
